UNITED STATES PATENT OFFICE.

AMBROSE T. MATTHEWS, OF WORCESTER, MASSACHUSETTS, ASSIGNOR TO MATTHEWS MANUFACTURING CO., OF WORCESTER, MASSACHUSETTS, A CORPORATION OF MASSACHUSETTS.

STOVE-URN.

SPECIFICATION forming part of Letters Patent No. 691,319, dated January 14, 1902.

Application filed October 29, 1901. Serial No. 80,436. (No model.)

To all whom it may concern:

Be it known that I, AMBROSE T. MATTHEWS, a citizen of the United States, residing at Worcester, in the county of Worcester and 5 State of Massachusetts, have invented a new and useful Stove-Urn, of which the following is a specification.

The invention relates to an improved cap-piece or ornamental urn for use on what are 10 termed "parlor heating-stoves."

The especial object of this invention is to provide a strong, simple, and inexpensive form of stove-urn in which the body-portion sections are fastened together and the side 15 brackets or handles are locked in place upon the body portion by a single fastening rod or bolt.

In the accompanying drawings, Figure 1 is a side view, partially in section, of a stove-urn constructed according to my invention, 20 one of the side brackets or handles thereof being shown in a detached position. Fig. 2 is a fragmentary view illustrating a modified form of construction. Fig. 3 is a fragmentary view illustrating a modified construction, the position of the fastening-lugs being 25 reversed from that illustrated in Figs. 1 and 2 and the key-shaped lug occupying the lower position instead of the upper position, as 30 shown in the previous figures; and Fig. 4 is a fragmentary view in which both lugs of the handle engage sockets in a single section of the body portion.

In connection with the older forms of heating-stoves it was usually customary to provide at the top of the stove an urn or vessel containing water for moistening the air.

In more recent forms of stoves the water vessel or urn has usually been replaced by an 40 ornamental top piece or ornamental urn which resembles the urn or water vessel which was formerly employed, but which is not usually desired to contain water. These ornamental top pieces or imitation urns usually 45 comprise a number of sections secured together by a fastening rod or bolt, which may also be employed for fastening the ornament onto the stove. When ornamental urns or stove-finished pieces of this class have here-

tofore been provided with ornamental handles or side brackets, these handles have usually been cast integrally with the body of the urn or have been secured to the body of the urn by rivets or other permanent fastenings.

The especial object of my present invention is to provide for securing the handles or side brackets of an ornamental urn in place by means of lugs or projections which fit into sockets in the body portion of the urn and are locked in place by the central fastening 55 rod or bolt, so that a single fastening serves for securing the body-portion sections together and for fastening the handles or side brackets thereto. To accomplish this result in a stove-urn constructed according to my 60 invention, the side brackets or ornamental handles are each provided with two extending lugs or projections. One of these lugs is preferably made in the form of a key having a toe-piece for engaging the inner side of one of the 65 body-portion sections, and the other lug consists, preferably, of a straight shank or projection which is not provided with a toe-piece. In securing a handle as thus constructed in place the key-shaped lug is first inserted into 70 its socket and the straight spur or projection is then locked in place in its socket by tightening the central fastening rod or bolt. I prefer to usually have the key-shaped lug engage the socket in one section of the body portion of the urn, while the straight lug engages a 75 socket in another section of the body portion of the urn, although the sockets for receiving said lugs may in some cases be located in a single body-portion section, the flange or edge of an 80 adjoining body-portion section being relied upon to lock the handle, as hereinafter described.

Referring to the accompanying drawings and in detail, a stove-urn constructed according to my invention, as illustrated in Fig. 1, comprises a body portion consisting of the knob formed by the sections A and B, with a central ball formed by sections C and D, and a base or stand formed by the sections E and 85 F. These body-portion sections are preferably stamped up from sheet metal and are secured together by a central fastening rod 90

95

or bolt G, having an ornamental harp H at its upper end and having a tightening-nut I at its lower end. The handles J employed in connection with a stove-urn of this form preferably comprises suitable scrollwork and are preferably formed from malleable castings. The handles J are provided at their upper ends, as shown in Fig. 1, with key-shaped lugs 10, having extending toepieces, and with straight projections or lugs 11 near their lower ends.

To secure the handles J in place, the nut on the central fastening rod or bolt is loosened, the key-shaped lugs 10 are fitted into their sockets in the body-portion section C, and the lugs 11 are fitted into their sockets in the body-portion section F. The nut I on the central fastening rod or bolt G is then tightened and serves not only to hold the body-portion sections together, but also serves to lock the handles in position.

In some cases instead of having the handle-lugs engage as widely-separated body-portion sections as the sections C and F, as shown in Fig. 1, the handles may be secured to the central ball of the body portion. For example, as illustrated in Fig. 2, the central ball of the body portion is of substantially the same construction as that illustrated in Fig. 1, except that its central band is formed from a separate piece or ring K.

The handle J', as illustrated in Fig. 2, is of a different shape from the handle J, (illustrated in Fig. 1,) and its lugs 10 and 11 fit into the sections C and D, respectively, so that the handle J' is fastened to the central ball of the body portion instead of extending down to the base.

In some cases also the relative position of the fastening-lugs extending from the handles may be inverted from that shown in Figs. 1 and 2. For example, as illustrated in Fig. 3, the handle J² has a straight lug 11, occupying a position above its key-shaped lug 10.

In the constructions as thus far described the handle-fastening lugs 10 and 11 of each handle engage recesses in separate body-portion sections. In some cases, however, the handle-fastening lugs may engage sockets in the same body-portion section, the handle being fastened in place by the overlapping edge of an adjoining body-portion section. This construction is illustrated in Fig. 4. As shown in this figure, the fastening-lugs 10 and 11 of the handle J³ fit into sockets, both of which are formed in the body-portion section D, the handle being locked in place by the overhanging flange of the section C, which is brought into engagement with the lug or

projection 11 when the fastening-nut on the fastening rod or bolt is tightened.

I am aware that other changes may be made in practicing my invention by those who are skilled in the art without departing from the scope thereof as expressed in the claims. I do not wish, therefore, to be limited to the constructions I have herein shown and described; but,

What I do claim, and desire to secure by Letters Patent of the United States, is—

1. In a cap-piece or ornamental urn for stoves, the combination of a body portion formed by separate sections or pieces, a central fastening rod or bolt, and handles having lugs fitting into sockets in the body portion and locked in place when the body-portion sections are drawn together by the fastening rod or bolt. 75

2. In a cap-piece or ornamental urn for stoves, the combination of a body portion 80 formed by separate sections or pieces, a central fastening rod or bolt, and handles, each having one lug engaging a socket in one of the body-portion sections, and a second lug engaging a socket in another of the body-portion sections, so that when the sections are drawn together by the central rod or bolt said handles will be secured in place. 85

3. In a cap-piece or ornamental urn for stoves, the combination of a body portion 90 formed by separate sections or pieces, a central fastening rod or bolt, and handles, each of which is provided with one key-shaped fastening-lug, and one straight fastening-lug, arranged to engage sockets in the body portion, so as to lock the handles in place when the body-portion sections are drawn together by the fastening rod or bolt. 95

4. In a cap-piece or ornamental urn for stoves, the combination of a body portion 100 formed by separate sheet-metal sections, a central fastening rod or bolt, and handles, each of which is provided with a key-shaped locking-lug engaging a socket in one body-portion section, and a straight lug or projection engaging a socket in a separate body-portion section, so that said handles will be locked in place when the body-portion sections are drawn together by the central fastening rod or bolt. 105 110

In testimony whereof I have hereunto set my hand in the presence of two subscribing witnesses.

AMBROSE T. MATTHEWS.
